US0D1105058S

(12) **United States Design Patent** (10) **Patent No.:** **US D1,105,058 S**
(45) **Date of Patent:** **** Dec. 9, 2025**

(54) **NOTEBOOK COMPUTER**

(71) Applicant: **Acer Incorporated**, New Taipei (TW)

(72) Inventor: **Jung-Wei Tsao**, New Taipei (TW)

(73) Assignee: **Acer Incorporated**, New Taipei (TW)

(**) Term: **15 Years**

(21) Appl. No.: **29/902,297**

(22) Filed: **Sep. 12, 2023**

(30) **Foreign Application Priority Data**

Mar. 25, 2023 (TW) 112301413

CLAIM

The ornamental design for a notebook computer as shown and described.

DESCRIPTION

FIG. 1 is a perspective view of a notebook computer showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view of the notebook computer in an alternate configuration; and,

FIG. 10 is another perspective view thereof.

The even-dashed broken lines shown in the drawings illustrate portions of the notebook computer that form no part of the claimed design.

1 Claim, 8 Drawing Sheets
